DESCRIPTION

FIG. 1 is a top right rear isometric view of a dual access load
mounting system showing the new design;

FIG. 2 is a top left front isometric view thereof;

FIG. 3 is a rear elevational view thereof;

FIG. 4 is a right elevational side view thereof, relative to
FIG. 3, with the left elevational side being a mirror image;

FIG. 5 is a front elevational view thereof;

FIG. 6 is a bottom plan view thereof with the top plan view
being a mirror image;

FIG. 7 is a top left rear exploded isometric view thereof;

FIG. 8 is a top right rear isometric view thereof in state of
use; and,

FIG. 9 is a top right rear isometric view thereof in an
alternative state of use.

(Continued)

The broken lines depict portions of the dual access load mounting system, which form no part of the claimed design. The broken lines showing an electronic device in a case of FIGS. 8 and 9 depict environmental subject matter and form no part of the claimed design.
